UNITED STATES PATENT OFFICE.

MARGARET H. SMYTHE, OF EVANSTON, ILLINOIS.

CURTAIN FIXTURE.

Application filed October 20, 1920. Serial No. 418,252.

To all whom it may concern:

Be it known that I, MARGARET H. SMYTHE, a citizen of the United States, residing at Evanston, in the county of Cook and State 5 of Illinois, have invented certain new and useful Improvements in Curtain Fixtures, of which the following is a specification.

This invention relates to curtain fixtures, and has for one of its objects the provision 10 of simple and efficient means for holding curtains or draperies in position upon their supporting rods.

Other objects will appear hereinafter.

It is customary to support window curtains or draperies upon metal rods secured 15 at the tops of window casings, the upper edge of the curtain or drapery being either provided with rings that encircle and slide upon the supporting rod, or with a tuck or 20 loop formed in the material of the curtain or drapery, through which tuck or loop the curtain rod is passed before being placed in its supporting brackets. The curtain rods are ordinarily of smooth polished metal 25 which offer little resistance to the sliding of the curtains upon them, and as a result there is a constant tendency for the curtain to creep along the rod, and, where a pair of spaced curtains are used, for the adjacent 30 edges to move toward each other. This is particularly true when the curtains hang in pleats or folds, and especially when the curtains are of relatively stiff material, or are starched so as to have some elasticity. This 35 tendency is accentuated by the blowing of curtains when the window is open. The result is that the curtains must frequently be adjusted upon the rods to prevent them from presenting an untidy and unsymmetrical appearance, and to prevent them from partially 40 or completely closing the window opening.

In the present form of the invention the curtain is held in position by providing an adjustable abutment or stop which may be 45 clamped upon the rod after the curtain is in proper position and the rod placed in its sockets, and which may be adjusted along the rod to any desired position. The adjustable stop is in frictional engagement with the

rod and engages the curtain, thus preventing 50 the above-mentioned objectionable movement or change of position of the curtain.

The preferred form of my invention is illustrated in the accompanying drawings, in 55 which—

Fig. 1 illustrates a front view of a window with curtains and a curtain rod equipped with my improved clip in position;

Fig. 2 is an enlarged fragmental view showing a portion of a curtain and curtain 60 rod equipped with my improved clip;

Fig. 3 is a view similar to Fig. 2 but showing rings securing a curtain to the rod;

Fig. 4 is a sectional view of the rod with 65 the clip in position upon it;

Fig. 5 illustrates the preferred form of 65 clip; and

Figs. 6, 7 and 8 show some of the alternative forms which may be used.

Referring now to the embodiment of my 70 invention illustrated in the drawings, a window casing 1 is provided with a pair of curtains 2 each curtain having a loop 3 slidably mounted on a rod 4 which is supported by two end brackets 5 secured to the window 75 casing. The curtains are illustrated as hanging in folds or pleats and as being parted or separated to leave the middle of the window space uncovered. Under these circumstances there is a tendency, previously referred to, 80 for the curtains to creep along the rod 4. This action is prevented by my improved curtain clips 6 which are clipped upon the curtain rod at the free edge of each of the curtains and which thus engage the edge 85 of the curtain (Fig. 2), or the curtain rings from which the curtain hangs (Fig. 3), to block or stop the movement of the curtains toward each other along the rod and hold them in the position to which they were 90 initially adjusted.

The form of clip which I prefer to employ is that which is illustrated in Fig. 5. This form consists of a resilient member, such as a piece of spring brass wire, bent 95 at its middle into an open-ended loop, the two arms of the loop at the same time being bent outwardly and then inwardly to

form jaws 7 having a slightly constricted mouth 8, the open end of the loop terminating in the prongs or projections 9 extending outwardly from the constricted or mouth portion 8. In placing this clip on the curtain rod 4 to occupy the position illustrated in Fig. 2, the clip is held by the shank or handle portion 10 and thrust laterally upon the rod, the diverging prongs 9 cooperating with the rod to wedge the jaws 7 apart to permit the entrance of the rod between them. The diameter or opening of the jaws 7 is normally a little less than the diameter of the rod with which the clip is to be used, so that when the clip is in place the jaws grasp the rod with sufficient pressure to develop the frictional resistance required to overcome the tendency of the curtain to move along the rod. The portion 10 of the clip that serves as a shank or handle also serves as a spring to hold the jaws in engagement with the rod. The prongs 9 in addition to their wedging or jaw-separating function, also act as stops or abutments for arresting the movement of the free edge of the curtain. The slight pressure of the free edge of the curtain against the prongs may tilt the clip slightly so as to throw the lower end or shank 10 within the outer edge or inside the loop of the curtain and thus hide it from view, see Fig. 2. For a $3/8$ " curtain rod, which is the diameter of the rod almost universally employed, the dimensions of the clip are substantially as illustrated in Fig. 5. The clip when in place therefore is so small as to be inconspicuous.

In order that the clip may be as small as possible consistent with doing the work for which it is designed, I have found it desirable to make the width of the constricted portion or mouth 8 only slightly less than the width or diameter of the jaws 7. When thus formed the clip may be forced upon the rod with relatively little spreading of the jaws. This makes it possible to reduce the length of wire in the shank 10 without causing the clip to be strained beyond its elastic limit and thus receive a permanent set in being applied to the rod. I have also found it desirable to make the space between the arms of the shank 10 relatively wide as compared with the other dimensions of the clip in order to simplify the forming operation.

In the alternative form of clip illustrated in Fig. 6 the jaws 7 are of angular instead of curved contour. In the form illustrated in Fig. 7 only one of the arms of the open-ended loop has an enlarged or outwardly and inwardly curved jaw portion, the other arm being straight. In the form shown in Fig. 8 the arms of the open-ended loop extend in straight lines from the jaw enlargement to the curved tip of the shank.

These alternative forms may be employed, but, as has been stated, the form shown in Fig. 5 is preferred.

When so desired a plurality of the clips 6 may be placed side by side on the rod 70 when the curtains are especially stiff to hold the latter against movements on the rod. The clips 6 may engage a curtain ring, as indicated in Fig. 3, as well as the edge of the curtain in Fig. 2, and be as effective. 75 Also, the clips may be applied to the rod so that the handle 10 engages the curtain or ring to provide the stop instead of the prongs 9.

I preferably form the sides of the handle 80 or spring 10 so that they converge toward the jaws 7. The connecting portions between the parts 7 and 10 provide a stop which prevents moving the clip too far onto the rod and thereby bending the parts 85 of the clip beyond their elastic limit.

I claim:

1. The combination with a curtain having a loop at its top and a curtain rod disposed in said loop and supporting the curtain, of a clip laterally placed upon and in frictional clamping engagement with limited opposite portions of the circumference of said rod, and being disposed at one edge of the curtain with a portion of said clip engaging one end of the loop, said clip being substantially within and hidden by said loop.

2. The combination with a curtain having a loop at its top and a curtain rod disposed in said loop and supporting the curtain, of a wire clip having portions intermediate its ends disposed partially around and frictionally engaging opposite sides of the curtain rod, said curtain engaging one end of the clip holding the latter at an angle to the rod and holding the greater part of the clip in the loop of the curtain.

3. A curtain clip comprising a resilient wire having a bend at its middle portion and its end portions disposed adjacent each other with a part of one of said end portions bent outwardly and then slightly inwardly to form a jaw with a slightly constricted mouth adapted to clamp opposite sides of a curtain rod, and the end portion of said clip beyond the slightly constricted mouth being adapted to engage the edge of a curtain and prevent sliding of the curtain on the rod.

4. A curtain clip comprising a light spring metal wire disposed with a handle portion having substantially straight and relatively widely separated sides, curved jaw portions adapted to grip opposite sides of a curtain rod and having a mouth the normal opening of which is only slightly less than the normal opening of the jaws, and curtain edge projection on said jaws diverging from each other.

5. A curtain clip consisting of a light resilient wire bent to form an open ended loop the sides of which are relatively widely separated, said loop being slightly expanded at an intermediate portion to form

jaws and provided with prongs at the open end of the mouth forming stops to hold a 10 curtain against sliding on the rod.

In testimony whereof I have signed my name to this specification on this 14th day of October, A. D. 1920.

MARGARET H. SMYTHE.
